UNITED STATES PATENT OFFICE.

ABRAM W. WHEATON, JR., OF MAPLEWOOD, NEW JERSEY, ASSIGNOR TO A. W. WHEATON BRASS WORKS, OF NEWARK, NEW JERSEY, A CORPORATION.

FAUCET WRENCH.

Application filed February 19, 1925. Serial No. 10,161.

To all whom it may concern:

Be it known that I, ABRAM W. WHEATON, Jr., a citizen of the United States, residing at Maplewood, in the county of Essex and 5 State of New Jersey, have invented an Improvement in Faucet Wrenches, of which the following is a specification.

The present invention relates to operating means for valves.

10 When dispensing gasoline and the like from a filling station or from a tank wagon, it is desirable to make provision for automatically shutting off the flow in the event of fire both to avoid loss of the product and 15 also to prevent feeding inflammable material to the flames.

The faucets commonly used for dispensing products of this character are of the self closing type, that is to say, of the type in 20 which the control valve is closed by the yielding pressure of a head of liquid or of a spring or weight and opened by means of a wrench operating against such yielding pressure to open the valve. One of the advantages of using faucets of the self closing type is to facilitate closing of the valve in 25 case of any accident. The operating wrenches used for opening the valves are intended either to be held open by the operative so long as the flow continues thus 30 requiring the continued attendance of the operative or to be held open by a suitable holding means. Even when no holding means is provided, the operative when filling 35 large tanks, in order to avoid standing by and holding the valve open, frequently secures the wrench in valve opening position by tying the handle thereof or by inserting a brace between it and some adjacent part of 40 the apparatus.

The present invention has for an object to provide a wrench for operating valves having provision whereby in event of fire the faucet valve will be automatically closed 45 even though the attendant has secured the handle of the wrench in valve opening position.

The nature and objects of the invention will be better understood from a description 50 of a particular illustrative embodiment thereof, for the purposes of which description reference should be had to the accompanying drawing forming a part hereof and in which—

55 Figure 1 is a side view of a self closing

faucet with a wrench embodying the invention applied thereto;

Figure 2 is a top plan view of the faucet and wrench shown in Figure 1; and

Figures 3 and 4 are detailed side views 60 showing the fusible link and the joint of the wrench before and after yielding of the fusible link.

In the structure shown the self closing faucet 5 has a horizontal valve operating 65 spindle 6 rotation of which in a counter-clockwise direction as shown in Figure 1 opens the faucet valve.

The wrench 7 is applied to the spindle 6 and movable downwardly in a plane at right 70 angles to the axis of the valve operating spindle to open the valve. As shown the wrench comprises two parts, a socket member 8 engaging the valve spindle, and a handle member 9 pivoted to the socket member 75 by a pivot pin 10, the axis of which is substantially parallel to the axis of the valve operating spindle 6 to permit relative movement of the socket member and handle member in the plane of normal operative movement of the wrench as it moves about the axis of the spindle 6 to operate the valve.

The socket member 8 is provided with a relatively long hub projecting on either side of the body of the socket member whereby 85 the wrench can be easily applied to the valve operating spindle when the same is in protected position within a recess for example as shown in the illustrative embodiment. The arrangement shown in which the hub projects on either side of the body portion of the socket member permits the wrench to be applied to either a right hand or left hand faucet.

The socket member and handle member 95 are rigidly connected, provision being made whereby the connection is automatically released by the application of heat. As shown, suitable lugs 11 and 12 are provided on the socket and handle members respectively adjacent the pivot and these lugs are rigidly connected by means of a fusible link 15. This link may comprise two parts connected by solder fusible at a low temperature. The opposite ends of this link are detachably 100 connected to the respective lugs by means of suitable screws. A suitable means may be provided if desired for temporarily holding the wrench handle in valve opening position. In the drawing there is shown a member 16 105

pivoted to the faucet and engageable with the handle member 9 of the wrench to hold the wrench in valve opening position.

In the event of fire the fusible link will 5 yield permitting the socket member to move on the pivot 10 relative to the handle member to permit closing of the valve. The fusible link 15 being separable as shown can be readily replaced in the event of damage or 10 breaking thereof from any cause.

The foregoing description of a particular form of wrench is intended as illustrative of the invention merely and is not to be construed as defining the limits of the invention.

15 I claim:

1. An attachable wrench for operating a self closing valve comprising a valve spindle engaging member and a handle member, and means rigidly connecting the valve spindle 20 engaging member and handle member comprising a detachable fusible link.

2. An attachable wrench for operating a self closing valve comprising a valve spindle engaging member, a handle member, and a 25 connection between said members comprising fusible material arranged to yield upon application of heat.

3. An attachable wrench for operating a self closing valve comprising a valve spindle 30 engaging member, a handle member pivotally connected thereto, and a fusible member holding the valve spindle engaging member and the handle member in fixed relation to each other.

35 4. An attachable wrench for operating a self closing valve comprising a valve spindle engaging member, a handle member pivotally connected thereto, the two members having laterally extending lugs on one side of 40 the pivotal connection and a fusible link connecting said lugs.

5. An attachable wrench for operating a self closing valve comprising a valve spindle

engaging member, a handle member pivotally connected thereto, and a rigid fusible 45 connection between said members eccentric to the pivotal axis.

6. An attachable wrench for operating a self closing faucet comprising handle and valve spindle engaging members pivotally 50 connected for relative movement in the plane of normal operation of the wrench and a fusible member rigidly connecting the handle and valve spindle engaging members whereby upon application of heat the operated member is released even while the handle is held.

7. In apparatus of the character described the combination with a self closing faucet having a valve operating spindle of a wrench comprising a socket member attachable to the valve operating spindle and a holding member pivoted thereto for movement relative to the socket member in the plane of normal operative movement of the wrench, 60 and fusible means for holding the socket member and holding member against relative pivotal movement, together with means engageable with the holding member to hold the wrench in valve opening position, whereby upon application of heat to said fusible means the valve operating spindle will be released to close the valve.

8. A valve operating wrench comprising a valve spindle engaging member, a holding member movably connected thereto and fusible means for preventing movement of the valve spindle engaging member relative to the holding member whereby upon melting of the fusible member the valve spindle engaging member may move.

In testimony whereof, I have signed my name to this specification this 30th day of January, 1925.

ABRAM W. WHEATON, JR.
